PROCESS FOR CONVERSION OF HYDROCARBON GASES AND OILS AND ABSORPTION SYSTEM THEREFOR

Gerald L. Eaton, Osborne, Pa., assignor to Gulf Oil Corporation, Pittsburgh, Pa., a corporation of Pennsylvania

Application October 31, 1938, Serial No. 238,019

2 Claims. (Cl. 196—8)

My invention relates to processes of conversion of hydrocarbon gases and oils and absorption systems therefor.

During the past few years, a number of processes have been developed for thermal conversion of normally gaseous hydrocarbons, such as propane, butane and the corresponding unsaturated hydrocarbons, to normally liquid gasoline-like hydrocarbons useful as motor fuel. Such conversion may be accomplished in conjunction with the pyrolytic conversion of hydrocarbon oil to gasoline, or separately. In the former instance, of which the so-called "gas reversion" processes are typical, the gases subjected to conversion along with the hydrocarbon oil to be cracked may consist entirely of gases produced in the system as a result of the decomposition of the hydrocarbon oil, but an increase in the amount and anti-knock value of the gasoline product may be secured by introducing gases into the system from an outside source. In straight gas-polymerization processes, all of the gaseous charge must, of course, originate elsewhere.

In either case, it has been found that only those normally gaseous hydrocarbons containing three and four carbon atoms per molecule should ordinarily be recirculated to the conversion zone. Hydrocarbons of higher boiling point represent gasoline constituents valuable as such, and recirculation thereof to the conversion zone simply tends to result in degradation of the gasoline product. On the other hand, hydrocarbons containing less than three carbon atoms per molecule, such as ethane, are too refractory in character. Consequently, in all such systems it is desirable to remove C₃ and C₄ hydrocarbons from the products of conversion as completely and sharply as possible, so that the normally gaseous hydrocarbons recycled to the conversion zone will contain all or substantially all of the C₃ and C₄ hydrocarbons, and yet be as free as possible from heavier and lighter hydrocarbons.

One of the objects achieved in accordance with my invention is to secure substantially complete and sharp recovery of C₃ and C₄ hydrocarbons, for subsequent conversion, in a system of the character set forth hereinabove, and more particularly one in which gases are introduced into the system from an outside source.

In accordance with my invention, the products leaving the conversion zone of a gas-polymerizing or combined oil-and-gas cracking unit, after separation of stabilized gasoline and heavier products therefrom, are subjected to contact in a primary absorption zone with a suitable absorbent

oil, and the thereby enriched oil, containing C₃ and C₄ hydrocarbons thereby absorbed, is delivered to the conversion unit for pyrolysis. The remaining gases are then delivered to a second absorber where any C₃ hydrocarbons remaining therein are removed by absorption in a second absorbent oil. This usually entails the absorption of a small amount of ethane.

Gases from an outside source, containing C₃ and C₄ hydrocarbons which it is desired to introduce into the conversion zone, are introduced into the system in a third absorber where they are scrubbed with a third flow of absorbent oil. This oil may be similar in character to that employed in the two absorbers mentioned hereinabove. In this third absorber, C₃ and C₄ hydrocarbons are removed from the aforesaid gases introduced from an outside source, by absorption. Enriched oil from the second absorber is introduced into the third absorber at an appropriate point corresponding as closely as possible to the point where the composition of the enriched absorbent flowing down through the absorber approximates the composition of the enriched oil from the second absorber. Due to the heat liberated by absorption of normally gaseous hydrocarbons in the third absorber, vaporization of undesirably light material contained in the enriched absorbent from the second absorber occurs. The combined flow of absorbent oil leaving the third absorber is then introduced into the conversion system.

In one specific embodiment of my invention, to be described more fully hereinbelow, the absorbent oil employed in the first absorber comprises light oil, such as naphtha or light gas oil, which is introduced from an outside source into the system to be cracked, and the absorbent oil employed in the second and third absorbers comprises a distillate oil produced in the system, the enriched oil from these absorbers being recirculated into the system at a point subsequent to the conversion zone. In such a system, it will be obvious that the normally gaseous hydrocarbons contained in the enriched oil leaving the third absorber are not delivered directly to the conversion zone, although they are ultimately picked up in the first absorber and delivered to the conversion zone for cracking and polymerization. One of the advantages of this type of system resides in the fact that the proportion of desired constituents in the vapors entering the first absorber is increased, and absorption is thereby rendered more efficient.

My invention may, however, be applied to other

specific types of units, such, for example, as a unit in which fresh oil from outside the system is available for use as an absorbing medium in the second and third absorbers as well as in the 5 first absorber, or to a system in which heavy naphtha or gas oil is produced in such quantity that such oil (after enrichment in the second and third absorbers referred to hereinabove) is delivered to a second conversion zone, the vapors 10 being combined with those from the primary conversion zone for fractionation and condensation and recovery of normally gaseous constituents therefrom.

In addition to the improvements referred to 15 hereinabove, other improvements in operative advantages and results will be apparent from consideration of the remainder of this specification.

In order that my invention may be more fully set forth and understood, I now describe, with 20 reference to the drawing illustrating and forming part of this specification, a preferred form and manner in which my invention may be practiced and embodied. In this drawing,

The single figure is a more or less diagrammatic and conventionalized elevational view of 25 apparatus for the thermal conversion of hydrocarbon oils and gases, adapted for the performance of my invention.

As shown in the drawing, this apparatus primarily comprises a cracking furnace 1, a tar separator 2, a fractionator 3, a condenser-stabilizer 4 and absorbers 5, 6 and 7, together with various conduits, pumps, valves and heat exchangers, to be described more fully hereinbelow. This particular system is especially suitable for the combined conversion of a light oil charging stock, such as naphtha or light gas oil, in conjunction with hydrocarbons containing three and four carbon atoms per molecule, in part derived from 30 an outside source and in part produced in the system.

A mixture of the oil charging stock and normally gaseous hydrocarbons containing three and four carbon atoms per molecule, derived in a 40 manner to be shown hereinbelow, enters the cracking furnace 1 through a line 10 and traverses an elongated pipe coil 11 of restricted cross-sectional area, wherein thermal conversion is effected at high temperatures and pressures. 45 Various temperatures and pressures may be used, so long as they are effective to promote a sufficient degree of conversion per pass of the charging stock, such as temperatures of from 900° to 1200° F. and pressures of from 200 to 3000 pounds 50 per square inch. However, optimum results are secured by employing temperatures sufficiently high to effect an increased degree of conversion per pass of the oil, over that which could be obtained, without serious carbon deposition, if the 55 oil were cracked alone in the same apparatus and under otherwise similar conditions of time and pressure, in the absence of normally gaseous hydrocarbons, all as set forth and described in the prior application of Povl Ostergaard Ser. No. 60 151,743, filed July 2, 1937, now Patent No. 2,135,014, dated Nov. 1, 1938.

The hot products of conversion leaving the coil 11 then pass through a transfer line 12 having a pressure-reducing valve 13 into the tar separator 2, which may be of more or less conventional design. It is usually desirable to check the reactions initiated in the coil 11 by introducing relatively cool oil to the products leaving the coil 11. In the instance shown, such quenching is 70 effected by delivering a flow of relatively cool

oil and normally gaseous hydrocarbons into the transfer line 12 through a quenching line 14. A similar flow of relatively cool material is also introduced into the tar separator 2 through a line 15. By virtue of this cooling and also by virtue 5 of the pressure reduction effected by means of valve 13, tarry constituents contained in the hot products of conversion are caused to separate out and are withdrawn from the tar separator 2 through a valved outlet line 16.

In the instance shown, in which the main charging stock is a light oil which upon conversion produces a relatively small amount of gas oil, such conditions are maintained in the tar separator 2 that all gas oil produced in the system is ultimately withdrawn in the tar leaving the system through the line 16. However, not all of the gas-oil constituents contained in the vapors traversing the tar separator 2 are initially condensed at this point; on the contrary, these 20 vapors contain substantial quantities of uncondensed gas-oil constituents, which must be condensed later in the system.

These vapors leave the tar separator 2 through a line 17 and enter the lower portion of the fractionating column 3, the interior of which is provided with suitable cooling means such as a water-cooled coil 18 and suitable gas-and-liquid-contact devices, such as a plurality of bubble trays 19. By means of cooling supplied through the coil 18 or otherwise, condensation of gas-oil constituents is effected, the gas-oil condensate being withdrawn from the bottom of the fractionating column 3 through a line 20 having a valve 21. This condensate is withdrawn at a rather high temperature, which must be lowered before the condensate can be used as an absorbent, and its further disposition will be shown hereinbelow.

Vapors leaving the top of the column 3, and now free from constituents having boiling points above the desired gasoline boiling-point range, then pass through a line 22 into the mid-section of the combined condenser-stabilizer 4. While various means may be employed for this purpose, the stabilizer-condenser 4 illustrated in the drawing, and which is preferred for use in this operation, is of that improved type set forth and described in the prior applications of Povl Ostergaard Ser. No. 52,717, filed Dec. 3, 1935, now Patent No. 2,134,926, dated Nov. 1, 1938, and Ser. No. 103,947, filed Oct. 3, 1936, now Patent No. 2,134,836, dated Nov. 1, 1938.

This unit, as shown, comprises an upper or condensing section 25 and a lower or stabilizing section 26. Unstabilized condensate is withdrawn from the lower portion of the upper section 25 through a line 27, is cooled in a heat exchanger 28 and is then delivered by a pump 29 through a line 30 into the upper portion of the condensing section 25, to serve as a cooling and refluxing medium therefor. Another portion of the unstabilized condensate condensed in the upper section 25 passes through a down-flow pipe 31 into the stabilizing section 26, where 65 rectification and stabilization occurs, assisted by a re-boiler 32 which is in communication with the bottom of the stabilizing section 26 through a liquid line 33 and a vapor-return line 34. Heat 70 for the operation of the re-boiler 32 may be supplied in various ways, but in the instance shown this heat is supplied by hot gas oil leaving the bottom of the fractionator 3, the gas-oil line 20 communicating with a heating coil 35 located in 75

the re-boiler 32. Stabilized gasoline is withdrawn from the re-boiler 32 through a line 36 having a valve 37 and passes out of the system.

Vapors liberated in the stabilizing section 28 5 pass upward into the condensing section 25 through a vapor line 38. Vapors leaving the top of the condensing section 25, and consisting of hydrocarbons having up to four carbon atoms per molecule, pass through a line 40 to a condenser 41 and thence into a separator 42, from which uncondensed vapors and condensate flow through lines 43 and 44, respectively, into the lower portion of the absorber 5.

Light gas oil or naphtha charging stock enters 15 the system through a line 45 and is delivered by means of a pump 46 and a line 47 into the upper portion of the absorber 5. As this oil flows downward through the absorber 5 it extracts from the 20 gases and vapors passing upward therein hydrocarbon constituents having three and four carbon atoms per molecule. Conditions within the absorber 5 are so maintained as to prevent absorption of substantial quantities of ethane in the absorbent oil, so that the enriched absorbent oil 25 leaving the bottom of the absorber 5 is substantially free from hydrocarbon constituents having less than three carbon atoms per molecule. This enriched oil then passes through a line 48 to a pump 49, which in turn delivers it through the line 10 into the coil 11 located within the cracking furnace 1.

The gases remaining unabsorbed in the absorber 5 pass through a line 51 to the lower portion of the absorber 6, where they are scrubbed 30 with a suitable absorbent liquid. In the instance shown, this liquid is provided by picking up hot gas oil leaving the coil 35 of the re-boiler 32 in a pump 52 which delivers it through a line 53 to a cooler 54 and thence through a line 55 and a branch line 56 having a valve 57 into the top of the absorber 6.

In order to insure complete removal of C₃ hydrocarbons from the gases traversing the absorber 6, conditions are so maintained within the absorber 6 that a small amount of ethane is also removed from the gases by absorption of the oil introduced through the line 56. The manner in which this ethane is subsequently removed will be shown hereinbelow.

Gases from an outside source, such as refinery 50 gases, cracking plant gases, natural gases or other gases containing substantial quantities of C₃ and C₄ hydrocarbons, enter the system through a line 60 communicating with the bottom of the absorber 7. A portion of the cool gas oil flowing through the line 55 is diverted into the upper part of the absorber 7 through a line 61 having a valve 62 and communicating with the line 55. As this oil flows downward through 55 the absorber 7, it absorbs C₃ and C₄ hydrocarbons from the gases, such conditions being maintained as to prevent any substantial amount of ethane from being contained in the enriched effluent leaving the bottom of the absorber 7 through a line 63. Enriched absorbent leaving 60 the bottom of the absorber 6 is withdrawn therefrom through a line 64, wherein is located a heat exchanger or cooler 65, and enters the absorber 7. This oil is introduced into the absorber 7 at such a point that the composition of the introduced oil approximates the composition of the liquid flowing down through the absorber 7 at the point of introduction, and sufficient cooling is ordinarily provided in the cooler 65 so that the 70 temperature of the introduced oil will also cor-

respond rather closely to the temperature of the oil flowing down through the absorber 7 at the point of introduction. Additional cooling for the absorber 7 may be provided by withdrawing a side stream from a trap-out tray 66 through a line 67 and returning this side stream through a cooler 68, a line 69, a pump 70 and a line 71 back to a higher level in the absorber 7.

However, due to the heat of absorption of normally gaseous constituents in the absorbent oil, 10 which is considerable on account of the relatively small amount of absorbent oil ordinarily employed, vaporization of ethane contained in the enriched absorbent oil introduced from the absorber 6 is readily effected, and the combined 15 absorbent oil leaving through the line 63 is substantially free from ethane, but contains substantial amounts of hydrocarbons having three and four carbon atoms per molecule as well as any heavier constituents which may be present 20 in the gases introduced through the line 66.

A portion of the enriched absorbent oil from the absorber 7, leaving through the line 63, then passes through a branch line 75 having a valve 76 to a pump 77 which in turn delivers it through 25 the line 14 into the transfer line 12, as a cooling and quenching medium. The remaining portion of the enriched absorbent oil passes through a branch line 78 having a valve 79 to a pump 80 which in turn delivers it through the line 15 30 into the tar separator 2 as a cooling and refluxing medium. Normally gaseous hydrocarbons contained in the oil thus re-introduced into the system are eventually picked up in the absorber 5 and recirculated to the conversion coil 11. 35

Gases remaining unabsorbed in the absorbers 6 and 7 are removed from the upper portions thereof through lines 82 and 83, respectively, and pass out of the system through an exit line 84 having a pressure control valve 85. By means of the valve 85, a suitable pressure is maintained 40 throughout the system so that the condensation and absorption operations referred to hereinabove may be conducted without difficulty and without the necessity for refrigeration. Such pressure 45 will ordinarily run from 100 to 500 pounds per square inch.

It will be understood that in referring hereinabove to "normally gaseous" hydrocarbons, I 50 means those hydrocarbons which, in isolated form, are gaseous at atmospheric conditions of temperature and pressure. They may, however, subsist in liquefied form in various parts of the cycle, due to the presence of absorbent oil, to pressure, or both.

While I have illustrated my invention hereinabove with reference to a specific embodiment and with reference to various operating and apparatus details, it will be understood by those skilled in the art that my invention is not limited to such details but may variously be practiced and embodied within the scope of the claims hereinafter made. 55

What I claim is:

1. The process of obtaining gasoline of high 65 anti-knock value from petroleum oil, which comprises: subjecting a mixture of petroleum oil and hydrocarbons containing three and four carbon atoms per molecule to cracking in a heated conversion zone, fractionating the vaporous products 70 of conversion to recover gasoline, tar and intermediate condensate contacting the remaining gases in a first absorber with said petroleum oil, prior to cracking the latter, to recover from said gases the bulk of the hydrocarbons containing 75

three and four carbon atoms per molecule, and cracking the resultant mixture of oil and absorbed hydrocarbons as aforesaid, contacting gases leaving said first absorber with a portion 5 of said intermediate condensate in a second absorber to absorb substantially all of the propane contained therein, together with some ethane, contacting a second flow of hydrocarbon gases in a third absorber with a further portion of said 10 intermediate condensate to remove hydrocarbons containing three and four carbon atoms per molecule therefrom, introducing enriched condensate from said second absorber into said third absorber and thereby vaporizing ethane from the 15 enriched condensate by the heat of absorption in said third absorber, withdrawing condensate enriched with hydrocarbons containing three and

four carbon atoms per molecule but substantially free of hydrocarbons containing one or two carbon atoms per molecule from said third absorber, and recirculating said condensate into the cycle at a point intermediate said heated conversion 5 zone and the point of recovery of said intermediate condensate from said products of conversion.

2. A process as claimed in claim 1, wherein the enriched condensate from said second absorber is 10 introduced into the third absorber at that point where the composition of the enriched condensate flowing down through the said third absorber most closely approximates the composition of the enriched condensate introduced from said second 15 absorber.

GERALD L. EATON.
